UNITED STATES PATENT OFFICE.

SIDNEY JAMES BROWN, OF LONDON, ENGLAND, ASSIGNOR TO SIDNEY JAMES BROWN AND WILLIAM GUY-PELL.

PERCUSSIVE HAND TOOL.

Application filed May 14, 1928, Serial No. 277,683, and in Great Britain May 14, 1927.

This invention relates to percussive drills embodying a hammer member operated by rotary means.

The object of the invention is to provide an improved device of the kind referred to with various features, which are individually advantageous, contributing collectively to the production of a tool combining lightness and compactness with effective percussion and a reduction of the usual recoil or vibration, as well as a tool which can be used to drill holes in corners.

The principal feature of the invention consists in the employment of a cam in the form of a single or multiple start buttress threaded helix or worm, working against a suitably shaped companion rack attached to the hammer member, which cam, in addition to being particularly smooth in action in producing reciprocation of the hammer may be conveniently used to produce rotation of the tool when desired.

But in order that the invention may be more readily understood and easily carried into effect it will now be further described with the aid of the accompanying drawings wherein Figs. 1 and 2 are views at right angles to one another of a percussive hand drill for use more particularly in boring holes in walls and the like intended to receive plugs into which screws are subsequently to be driven. Fig. 3 is a sectional view of a portion of Fig. 1 and Fig. 4 is a corresponding view with the parts in another position. Fig. 5 is another view of one of the elements of Fig. 3 and Fig. 6 is another view of one of the elements removed from Fig. 1.

As here shown, a drill 1 is inserted in a holder 2 the stem 3 whereof is an easy fit within a sleeve 4 attached to, or forming part of, a frame 5 provided with a handle 6, pressure applied to which will be transmitted by way of the sleeve 4 to the holder through the shoulder of the latter. 7 is the hammer head fixed by a screw 8 to a lever 9 pivoted at 10 between the jaws of a forked bracket 11 which may be removably secured to the frame 5 as by a set screw. This lever 9 is acted upon by a helical spring 12 encircling a stationary post 13 which passes through an aperture 14 in the lever and is furnished with a nut 15 having a milled edge and adapted to vary the force exerted by the spring upon the lever. For the purpose of retracting the lever it is provided with a rack 16 having teeth more or

less complementary to four buttress threads 17 constituting a worm adapted to be rotated by a crank handle 18 upon a spindle 19. This spindle 19 may conveniently work in bearings 20, 21, the bearing 20 being permanently attached to the frame 5 and the other bearing 21 removably secured, as by a set screw 22.

The rack 16 is preferably secured to the lever 9 by a screw threaded stem 23 and nut.

For the purpose of continuously rotating the drill, a worm wheel 24 (Figs. 1 and 6) is fixed upon the stem 3 of the drill holder, said wheel having teeth adapted to mesh with the worm 17. The boss 25 of this wheel positions the tool holder stem 3 in the sleeve 4 with a certain amount of clearance at 26.

When the tool is not in use the rack 16 bears fully upon the worm 17 and the lever 9 will in consequence be inclined somewhat towards the front of the frame and not as illustrated, so that there is clearance between the tool holder 2 and the sleeve 4 which disappears when, as assumed, pressure is applied to the handle 6 whilst using the tool. In other words, when the tool is in use the parts occupy the position shown where the end of the stem 3 engages the screw 8 and has slightly displaced the lever 9 and hammer head 7. In this way jar between the worm and rack during operation is lessened.

From the foregoing it will be understood that as the crank handle 18 is turned, the worm threads 17 acting upon the rack 16 after the manner of a screw thread upon a part nut held against axial movement, will gradually displace the rack and its lever 9 from the position shown in Fig. 3 to that shown in Fig. 4 after which the rack 16 and lever 9 are liberated and allowed to return rapidly under the action of spring 12, thus imparting a sharp blow to the stem 3 of the tool holder 2. The use of a multiple worm thread enables a series of blows to be imparted per revolution of the cam. Thus whereas in the case of a single helix or worm thread it is necessary, for continuity of action, that the rack shall be liberated at the completion of a revolution, four threads as in the example illustrated enables the rack to be liberated at the completion of each quarter revolution.

By reason of the employment of the lever 9 and location of the spring 12 near its pivot, a strong spring can be employed the compression of which is completed with movement through a relatively small distance, the

hammer head 7 on the other hand moving through a much greater distance and more rapidly due to the difference in the leverage movements. A very effective percussive action thus results, and it will be found that the recoil of the frame is materially reduced. The fact furthermore that the cam acts upon the lever 9 at a greater distance from the pivot 10 than does the spring 12 lessens the pressure exerted between the cam and the rack 16.

The whole arrangement is such that the axis of the worm 17 can be disposed midway, or substantially midway, between the major limbs of the frame 5 so that the crank handle 18 is located approximately centrally of the holding handle 6, and the axis of the tool holder can be located nearer to one such limb of the frame than to the other, thus enabling holes to be drilled close to obstructions in different planes such as are formed by the side wall and ceiling at the corner of a room for example. The crank handle 18 is formed with a screw threaded hole so that it can be quickly applied to and removed from a screw threaded projecting end of the worm spindle 19.

In some cases the crank handle 18 may be extended, as indicated in dot and dash lines 30 in Fig. 3 and formed with a second screw threaded hole, or holes, to enable the length of the driving arm to be varied. Also if desired the spindle 19 may, as shown in Figs. 2, 3 and 4 be extended at the opposite end to enable the handle 18 to be fitted thereto when opposite handed corners are for example being dealt with, the said spindle end having a left hand thread and the handle 18 provided with an additional hole as at 18^a

also with left hand thread. Or two separate 40 handles may be employed.

If desired the parts may be enclosed to a greater or lesser extent, two cover plates 27 being illustrated as fitted for that purpose.

It is to be understood that various modifications can be effected.

The construction of the tool is such that removal of the principal parts can be readily effected.

What I claim is:—

1. A tool of the kind referred to, comprising a frame, a hammer head, resilient means through which the head reacts against the frame, a member embodying a rack to which the hammer head is secured, a buttress threaded worm cooperating with the rack and adapted to retract the hammer head therethrough, and means for manually rotating the worm, substantially as described.

2. A tool according to claim 1, wherein the member to which the hammer head is secured is angularly movable.

3. A tool according to claim 1 wherein the member to which the hammer head is secured is a lever pivoted at one end and the resilient means through which the head reacts against the frame is disposed between the head and the pivotal connection of the lever.

4. A tool according to claim 1 wherein the worm is formed by a multi-start thread.

5. A tool according to claim 1 wherein a tool holder is employed having a worm wheel adapted to be engaged and rotated by the worm which retracts the hammer.

Signed at London, England, this 21st day of April, 1928.

SIDNEY JAMES BROWN.
